UNITED STATES PATENT OFFICE

2,443,906

PROCESS FOR THE MANUFACTURE
OF ETHERS

Henri Martin Guinot, Versailles, and Jean Gardais, Saint-Romans-les-Melle, France, assignors to Les Usines De Melle (Societe Anonyme), Saint-Leger-les-Melle, France, a company of France

Application March 17, 1945, Serial No. 583,377
In France March 26, 1943

4 Claims. (Cl. 260—614)

1

It is well known that the classic method of manufacture of sulphuric ether through catalytic dehydration of alcohol by means of sulphuric liquors entails difficulties as a consequence of by-reactions which are detrimental to the yield: for instance production of ethylene due to the fact that the etherifying reagent is too strong, and formation of sulphurous acid from sulfuric acid which is reduced by organic materials in the reactant medium. Both reactions are always accompanied with a more or less accentuated browning of the etherifying bath, which discloses other undesirable by-reactions, such as resinification of acetaldehyde transiently formed by oxidation of alcohol.

In industrial practice, etherifying baths are generally a mixture of equal volumes of sulphuric acid of 66° Bé. and of 96.6 per cent alcohol (i. e. 70 parts by weight of acid for 30 of alcohol). At first, such a mixture has a very good activity provided water and ether are taken away by distillation in proportion to their being formed. However, the use of such a mixture does not allow of completely avoiding the above mentioned by-reactions; any slight variation in the percentage of alcohol or in the temperature of the etherifying mixture causes a considerable increase of the amounts of ethylene and sulphurous acid, with strong blacking of the bath.

Besides, lead generally forming the inner lining of the etherifying boiler is severely corroded, so that it is not unfrequent to find it out of use after less than 24 hours; at least, the purity of ether is not always good.

In order to do away with these disadvantages, it has been proposed to operate in quite anhydrous medium, by adding to the etherifying bath a hydrocarbon adapted to play the part of a water entrainer. Reaction equilibrium is then constantly shifted in a direction favourable to rapid etherification and it is possible to work at a lower temperature.

This method enables of obtaining a very large activity of the etherifying bath; it is possible, for instance, to obtain in a continuous process, a daily amount of ether attaining 15 times the weight of the bath in use, with a temperature of etherification not higher than 115 to 120° C. However, let alone an increased consumption of steam, a drawback of the method is that the use of lead should be prohibited as it is acted upon by anhydrous sulphuric acid; likewise special steels should be avoided as they are rapidly corroded when after ups and downs of any kind during distillation, the bath grows momentarily

2

richer with water. It is then necessary to resort to enamelled vessels but the latter have an insufficient heating surface and enamel scales off readily.

5 We have now found that when working in accordance with the conventional method without any entrainer, it is possible to do away with the above drawbacks, provided one uses baths which contain a relatively large, predetermined proportion of water, owing to which lead is no longer corroded and becomes fit for lining purposes. As a matter of fact, we have unexpectedly found that as concerns corrosion, everything happens as though the titre of sulphuric acid, i. e. the ratio 10 sulphuric acid: sulphuric acid+water, is concerned alone and the actual proportion of alcohol and ether in the mixture practically plays no part in this respect. Thus very concentrated sulphuric acid is always offensive, even where 15 diluted in a large proportion of alcohol and ether.

20 On the other hand, an acid having a titre lower than 75 to 80 per cent is practically without any action on lead in the conditions of temperature adopted.

25 We have further found that in contradistinction with any expectation, these baths relatively rich in water are still capable of causing etherification of alcohol at a sufficient rate. Thus, 60 per cent sulphuric acid mixed with so much alcohol as to secure a boiling point of 130° C. (i. e. 30 5 per cent by weight) yields an etherifying bath capable of producing every day in a continuous process, one time and a half its weight of ether. With 65 per cent acid the production reaches 35 4 times the weight of the bath, assuming that the same temperature of 130° C. has been obtained by adding 12 per cent by weight of alcohol. With 70 per cent acid admixed with 20 per cent by weight of alcohol, the daily amount of ether 40 produced is more than 6 times the weight of the bath, when working at 130° C.

Practically it is advisable to use 65 to 70 per cent acid so as to keep a good margin for safety against corrosion of lead. It is then only necessary to rectify the vapors evolving out of the etherifying vessel with a view to separating ether from accompanying alcohol and water.

45 The proper composition of the bath once determined, it is necessary to keep this composition 50 unaltered in a continuous process in order to avoid an accidental accumulation of water which would cause the reaction speed quickly to fall, as well as a failure of water, even momentary, which would cause incipient corrosion of lead and generation of ethylene and sulphur dioxide. To

this end, a substantially constant heating of the etherifying vessel being provided, the temperature of the bath is adjusted to the predetermined value (practically 125 to 130° C.) by controlling the rate of alcohol supply, and water is sent back to the etherifying vessel by a proper amount to keep a constant volume of bath; any substantial variation of this volume would mean a disadjustment, the origin of which could readily be detected from an analysis of vapors and, should it so happen, of the etherifying bath. It is thus possible to come to an almost mathematical control of the run of the apparatus. The yield is then close to the theoretical one (99 per cent). The amount of ethylene produced is very small. Besides no trace of sulphur dioxide is found, so that the conventional saturator may be omitted. The etherifying bath is little coloured and after several weeks of full-rate work, it has only a light brown hue.

As to ether, its purity is substantially higher than that of the product obtained according to the classic method. It is slightly hydrated (0.7 to 0.8 per cent) and includes only traces of acid, aldehyde and peroxides. No trace of sulphurous compounds is found; with Nessler's reagent, it gives only a light yellow tint, while the ether obtained by the classic method generally gives very quickly with this reagent, a dark brown and very often a black coloration.

The following description with reference to the appended drawing given solely by way of example will better show how this invention may be carried out.

The drawing is a diagrammatic view of a suitable apparatus for carrying out our method.

In the etherifying boiler 1, of a capacity of 1200 litres, provided with a heating device 2, we poured 1000 kg. of 68 per cent sulphuric acid together with the necessary amount of alcohol, to bring the boiling point of the mixture near 130° C., that is to say about 180 kg. While the mixture boiled, we continuously introduced alcohol from tank 4 into boiler 1 through pipe 3 at the required rate. Alcohol was previously passed through a scrubber 15, the purpose of which will herein-after be explained. The vapors from boiler 1 first passed through a foam-breaker 5, then into the middle part of the column 6, which was heated at its base at 7 and in which the vapors were rectified. From the upper part of said column, a few plates under the top, vapors of ether were drawn out through pipe 8. After condensation at 9, ether was collected in a tank 10. Volatile impurities, particularly acetaldehyde, were gathered on the upper plates of column 6 and after condensation at 11, were withdrawn from 12 at the proper rate. Water produced during the reaction was withdrawn through pipe 13 from the base part of the column.

As for uncondensable gases essentially consisting of small amounts of ethylene formed during the reaction, they evolved from condenser 11 through pipe 14. These gases being saturated with ether vapors to be recovered, were delivered to a first scrubber 15, where they were washed with alcohol fed to boiler 1, then to a second scrubber 16 where any alcohol carried along was recovered by means of water sprinkling therethrough. Ethylene free from soluble products escaped through pipe 17 and could be stocked in a gasometer.

In order to ease up condenser 11, which worked in unfavourable conditions by reason of the low temperature of the vapors to be condensed, it

was found advantageous to provide an auxiliary condenser 18 for cooling vapors drawn through pipe 19 from a point at about the $\frac{2}{3}$ of the height of the column, said vapours being a mixture of ether and alcohol. A part of liquid condensed at 18 was returned through pipe 20 to the plate just below pipe 19, the remainder being sent back to boiler 1 through pipe 21.

In order to secure a constant proportion of water in the etherifying bath, a pipe 22 provided with a cock, allowed us to return to boiler 1 a part of the washing water from scrubber 16. It is also possible to use for this purpose a part of the hot washes leaving the base of column 6 at 13. Said washes may be supplied to vessel 1 through pipe 23 provided with a control cock as shown.

It should be understood that our invention is not confined to the use of the apparatus above described, as this description has been made only as a non-limitative example.

The ether obtained in accordance with our method is characterized, as already set forth, by a higher purity than that of the product made according to classic method; consequently it is particularly adapted to be used as a raw material for production of anaesthetic ether.

While we have described our invention in detail, the embodiment given in the description and the drawing being only for example, it will be obvious to those skilled in the art, after understanding our invention, that various changes and modifications may be made therein without departing from the spirit or scope thereof.

What we claim is:

1. A continuous process for the production of ether, which comprises boiling in a reaction zone a mixture of alcohol and an aqueous solution of sulphuric acid having a strength in the range of 60 to 80 per cent in such a relative proportion that the mixture boils at a temperature in the range of about 120 to 135° C., thus producing gas and vapors in said reaction zone; continuously removing said gas and vapors substantially wholly and in uncondensed condition from said reaction zone without reflux; and continuously adding alcohol and water to said mixture in calculated proportions to keep said strength and temperature substantially constant within said ranges.

2. The process of claim 1, further comprising the steps of separating said gas and vapors in a second zone separate from said reaction zone, into gas, water, ether and a substantially anhydrous mixture of ether and alcohol; and continuously returning said mixture of ether and alcohol to said reaction zone.

3. The process of claim 1, further comprising the steps of introducing said gas and vapors into the middle portion of a distillation zone so as to cause gathering of water in the bottom part of said distillation zone, a substantially anhydrous ether-alcohol mixture at a point in said distillation zone above the point of introduction of said gas and vapors, pure anhydrous ether above said ether-alcohol mixture in said distillation zone, and volatile impurities and gas at the top of said distillation zone; continuously and separately withdrawing said water, ether-alcohol mixture, pure anhydrous ether and volatile impurities with gas, from said zone; and continuously returning said ether-alcohol mixture to said zone.

4. In the continuous production of ether from alcohol and an aqueous solution of sulphuric acid having a strength in the range of 60 to 80 per cent, the step of continuously adding water in a

calculated proportion to compensate for steam evolution and keep said strength within said range, to a boiling mixture of said alcohol and said aqueous solution in such a relative proportion that said mixture boils at a temperature in the range of about 120 to 135° C.
